CLAIM

The ornamental design for a paint can holder, as shown and described.

DESCRIPTION

FIG. 1 is a front perspective view of the paint can holder of the present invention showing our new design.

FIG. 2 is a front elevation view of the paint can holder shown in FIG. 1.

FIG. 3 is a side view of the paint can holder shown in FIG. 1, the opposite side of which is identical.

FIG. 4 is a top plan view of the paint can holder shown in FIG. 1; and,

FIG. 5 is a bottom plan view of the paint can holder shown in FIG. 1.

The broken line showing of the can holder with adjustment holes is included for the purpose of illustrating and forms no part of the claimed design.
